UNITED STATES PATENT OFFICE.

WILLIAM STANLEY, JR., OF GREAT BARRINGTON, MASSACHUSETTS, ASSIGNOR
TO THE WESTINGHOUSE ELECTRIC COMPANY, OF PITTSBURG, PENNSYLVANIA.

REGULATION OF ELECTRIC MOTORS.

SPECIFICATION forming part of Letters Patent No. 392,890, dated November 13, 1888.

Application filed May 13, 1887. Serial No. 238,135. (No model.)

To all whom it may concern:

Be it known that I, WILLIAM STANLEY, Jr., a citizen of the United States, residing in Great Barrington, in the county of Berkshire and State of Massachusetts, have invented certain new and useful Improvements in the Method of Regulating Electric Motors, of which the following is a specification.

In the accompanying drawings, which make part of this specification, Figure 1, Sheet 1, is a diagrammatic view of an electric motor and a regulating apparatus illustrating the application of my invention when a constant quantity of current is supplied; Fig. 2, Sheet 2, a similar view illustrating the application when a constant difference of potential is supplied; and Figs. 3 and 4, similar views exemplifying modifications in the arrangement of the demagnetizing-circuit.

The object of my invention is to effect the regulation of an electric motor to a determined constant speed, as may be required by the work to be performed by the motor, so as to prevent variation of speed under increase or diminution of duty or load.

To this end my invention, generally stated, consists in a novel method of increasing and decreasing the development of energy from an electric motor in accordance with and proportionately to variations in the work or load imposed by automatically decreasing and increasing the electro-magnetic effect of a demagnetizing-circuit upon the field of the machine.

In the operation of electric motors it is desirable, and in many cases essential to a proper and effective performance of their work, that a uniform speed should be maintained irrespective of the temporary variations in the resistance imposed by the partial cessation or the additional imposition of work, as in the case of the illumination of a greater or less number of electric lights or the operation of more or less machinery from time to time. Motors employed in such service may be operated under either of two different conditions—first, where the electric energy actuating the motor is supplied as a constant quantity of current flowing through a line, in which case the electro-motive force applied to the terminals varies as the work performed; and,

second, where a constant electro-motive force or difference of potential is applied to the terminals of the motor, in which case the quantity of current flowing through the motor will be varied proportionately with variations in the work.

My invention, which is equally applicable under either of the above-stated conditions, affords ready and effective means for insuring the maintenance of such speed of the motor as may be suitable or requisite for the performance of the particular duty to which it is assigned.

Referring first to the case of a motor adapted to use in a line supplied with a constant quantity of current, Fig. 1 illustrates a construction adapted to the practice of my invention. The motor, which may be of any suitable and preferred construction, is here shown as provided with magnet-cores 10 11, provided with pole-pieces 12 13, between which an armature, 14, is adapted to rotate in the usual manner. The electric current which actuates the motor passes from a generator or other suitable source of supply through an energizing-circuit composed of a wire, 1, connected to one of the terminals 8, a wire, 2, wound upon the magnet-cores 10 11, and leading from the terminal 8 to one of the brushes 15 of the armature 14, a wire, 3, wound around a regulating electro-magnet, 4, and extending from the other brush, 16, to the opposite terminal 9, and a wire, 5, leading from the terminal 9 to the generator. A demagnetizing-circuit, which is practically a shunt across the terminals of the motor, is formed by a finer wire, 6, leading from the terminal 8 and wound around the magnet-cores 10 11 to a connection with a resistance line or coil, 7, from which a series of connecting-wires, 17, extend at different points in its length to 90 contact-plates 18. The demagnetizing-circuit on the opposite side of the resistance line or coil 7 extends through an automatic switch-lever, 20, pivoted at one end by a link, 23, to the armature 22 of the regulating-magnet 4, 95 and adapted to make contact, as raised or lowered by the movements of the armature, with either of the different contact-plates 18, and wires 24 25 lead from the switch-lever 20 to the terminal 9 of the motor. The fine wire of 100

the demagnetizing-circuit is of comparatively high resistance relatively to the coarser wire of the energizing-circuit, and consequently takes a smaller portion of the current, and when the motor is in motion the quantity of current flowing through the demagnetizing-circuit is proportional to the counter electro-motive force of the motor, and the resistance of the energizing-circuit is less than that of the demagnetizing-circuit. When the current is turned on the motor from the generator, the regulating-magnet 4 raises the switch-lever 20 and holds it with its free end in contact with the plate 18, which is connected with the farther extremity of the resistance-line 7, thereby throwing a maximum of resistance into the demagnetizing-circuit until the motor has obtained, through the revolutions of its armature, sufficient counter electro-motive force to cause the resistance of the energizing-circuit through the wires 2 3 to exceed that of the demagnetizing-circuit through the wire 6, resistance-line 7, connection 17, contact-plate 18, switch-lever 20, and wires 24 25. Such increase of resistance, by demagnetizing the regulating-magnet 4, allows the switch-lever 20 to fall back to the position shown in the drawings, in which the minimum of resistance is shunted into the demagnetizing-circuit and the demagnetizing effect of said circuit is at its maximum, such demagnetizing effect tending to reduce the counter electro-motive force by demagnetizing the field of the motor-magnet.

If now a load be added, the amount of current flowing through the energizing-circuit will be increased by reason of the decrease of counter electro-motive force due to the slowing up of the armature. This increase of current excites the regulating-magnet 4 and causes it to lift the switch-lever 20, thereby increasing the resistance of the demagnetizing-circuit by throwing in a greater length of the resistance line or coil 7, such increase of resistance correspondingly increasing the speed of the motor both by reason of the decrease of the demagnetizing effect of the demagnetizing-circuit, and of the increase of the magnetizing effect of the energizing-circuit due to the arrangement of the two circuits as shunts to each other. The movement of the switch-lever in the direction to increase resistance continues until the counter electro-motive force has risen sufficiently to decrease the quantity of current through the energizing-circuit and thereby to stop the upward pull of the magnet. If, on the other hand, the mechanical load be decreased, the revolutions of the armature will be momentarily increased, the counter electro-motive force will be increased, and the regulating-magnet 4 will thereby be weakened. The resistance of the demagnetizing-circuit will consequently be decreased by the lowering of the switch-lever and a greater quantity of current be permitted to flow through said circuit, such increase of current demagnetizing the magnets of the motor and reducing its speed to the degree required.

Fig. 2 illustrates a construction applicable in cases where a constant difference of potential between the terminals 8 9 of the motor is employed. The current of the energizing-circuit passes through the wire 1 to the terminal 8 of the motor, thence through the wire 2, wound upon the magnet-cores 10 11, to one of the brushes 15, and from the other brush, 16, 75 through a wire, 3, wound upon the regulating-magnet 4, to a connection, 26, at which it is divided, a portion passing through a demagnetizing-circuit composed of a wire, 27, leading to a binding-post, 28, on the motor, and a wire, 6, leading from the binding-post 28 to the terminal 9 and wound upon the magnet-cores 10 11. The other portion of the current passes as a shunt to this circuit having a variable resistance formed by the wire 29, 85 switch-lever 20, contact-plates 18, connections 17, resistance line or coil 7, and wire 30.

When current is not turned on to the motor, the armature of the regulating-magnet not being attracted the connected end of the switch-lever is in its lowest position, as shown in the drawings, and consequently the maximum resistance is thrown into the shunt-circuit.

Upon the application of a current to the motor, the regulating-magnet 4, being excited, lifts 95 the switch-lever 20 and by cutting out a portion of the variable resistance allows a greater quantity of current to flow through the shunt-circuit wires 29 30 to the terminal 5 and a less quantity through the demagnetizing-circuit, and the motor consequently increases its speed until the counter electro-motive force rises sufficiently to reduce the strength of the regulating-magnet and increase the resistance of the shunt-circuit to the required degree. 105 Under such construction the strengthening of the regulating-magnet cuts out resistance in lieu of throwing in resistance, as in the case first described, but in both the same result—to wit, the reduction of the effect of the demagnetizing-circuit is attained by the strengthening of the magnet.

It will be obvious that the arrangement of circuits may be modified in sundry particulars without departing from the spirit of my 115 invention so long as a regulating-magnet and variable resistance are employed to vary the field-strength of a motor by varying the strength of a demagnetizing-current—as, for example, the regulating-magnet may be arranged in the 120 direct circuit of the motor, in shunt to the motor or in shunt to the armature of the motor.

In Figs. 3 and 4 the regulating-magnet is connected in shunt to the armature of the motor by wires 33, and the demagnetizing-circuit and its variable resistance is arranged in Fig. 3 as a shunt to the terminals of the motor, and in Fig. 4 as a shunt to the terminals of the armature. In each case the magnetic strength of the regulating-magnet increases 125 when the counter electro-motive force of the armature is highest, while in the construction shown in Figs. 1 and 2 the magnetic strength of the regulating-magnet decreases when the

counter electro-motive force is highest. Again, in Fig. 3 the upward movement of the armature of the regulating-magnet decreases the variable resistance, while in Fig. 1 the upward movement of said armature increases the variable resistance.

The specific regulating mechanism herein shown does not *per se* constitute part of my present invention, and need not therefore be at length described, as other devices may be equivalently employed in the practice of my invention to attain the result effected thereby. Said mechanism, moreover, constitutes the subject-matter of another application for Letters Patent filed by me.

I claim as my invention—

1. The improvement in the method of regulating the speed of electric motors, which consists in automatically varying the electro-magnetic effect of a demagnetizing current upon the

field of the motor by introducing variations of resistance in said circuit coincidently with and proportionately to variations in the mechanical duty of the motor, substantially as set forth.

2. The hereinbefore described method of governing electromotors, which consists in automatically varying the current traversing a demagnetizing-circuit applied to the field-magnet of the motor by varying the resistance of said circuit coincidently with and proportionately to variations in the mechanical duty of the motor.

In testimony whereof I have hereunto subscribed my name this 30th day of April, A. D. 1887.
